UNITED STATES PATENT OFFICE.

JOHN S. BLAKELY, OF WELLINGTON, KANSAS.

GRAIN-METER.

No. 895,234.

Specification of Letters Patent.

Patented Aug. 4, 1908.

Application filed December 6, 1907. Serial No. 405,431.

To all whom it may concern:

Be it known that I, JOHN S. BLAKELY, citizen of the United States, residing at Wellington, in the county of Sumner and State of 5 Kansas, have invented certain new and useful Improvements in Grain-Meters, of which the following is a specification.

The present invention relates to improvements in grain meters and aims to provide a 10 device of this character which can be readily utilized in connection with threshing machines, grain elevators and the like for quickly and accurately determining the quantity of grain discharged from the same.

15 The invention further contemplates a grain meter which is simple and inexpensive in its construction and which embodies a compact mechanism adapted to be installed in a comparatively small amount of space.

20 For a full description of the invention and the merits thereof and also to acquire a knowledge of the details of construction and the means for effecting the result, reference is to be had to the following description and 25 accompanying drawings, in which:

Figure 1 is a side elevation showing the improved grain meter mounted in coöperative relation to a grain elevator. Fig. 2 is an enlarged detail view of the scale beam. Fig. 3 30 is a vertical sectional view through the device. Fig. 4 is a transverse sectional view through the rotary hopper. Fig. 5 is a similar view through the upper portion of the casing inclosing the hopper.

35 Corresponding and like parts are referred to in the following description and indicated in all the views of the drawings by the same reference characters.

The grain meter embodied by the present 40 invention is designed to be employed in connection with any conventional type of threshing machine, separator or the like and for the purpose of illustration is shown in the present instance as mounted to receive grain 45 from the delivery spout 1 of an elevator 2. In general the meter comprises a rotary hopper journaled directly upon a scale beam, means being provided for locking the hopper against rotation when overbalanced by the 50 poise upon the scale beam and held in an elevated position, and for releasing the hopper to permit of the rotation thereof and the consequent discharge of the grain therefrom when the weight of the grain becomes sufficient to 55 overbalance the poise and depress the hopper. As shown on the drawings this rotary

hopper embodies the circular end pieces 3 connected by the radial partitions 4 subdividing the hopper into a plurality of compartments designed to be brought successively into an operative position as the hopper is rotated. In the present instance the end pieces 3 are joined by four of the radial partitions and a corresponding number of the compartments 5 are formed. This hopper is journaled between the two arms of a U-shaped scale beam 6 at the extremities thereof, and the said arms of the scale beam are pivotally mounted at an intermediate point upon slotted standards 7 projecting upwardly from corresponding points upon horizontal bars 8 at opposite ends of the hopper. These bars 8 support an approximately semi-cylindrical casing 9 inclosing the upper portion of the hopper, the ends of the casing being formed with flanges 10 fitting closely around the edges of the disks 3 so as to prevent any leakage of grain between the said members. This casing 9 is provided at its upper portion with a stop 11 designed to engage projections 12 upon the rotary hopper and to hold the various compartments of the hopper successively under the delivery spout 1 of the grain elevator. These projections 12 are preferably in the nature of cross bars connecting 70 opposite sides of the hopper.

The outer end of the scale beam 6 is constituted by a cross bar located upon the exterior of the casing 9 and carrying a weight 13 designed to counterbalance the hopper 90 and normally hold the same in an elevated position so that the stop 11 is disposed in the path of the projections 12. Adjustably mounted upon each of the arms of the scale beam is a poise 14 for determining the weight of the grain which must be discharged into the hopper before the latter will be depressed sufficiently to release the projection 12 from engagement with the stop 11 and permit the hopper to rotate and discharge the grain 100 therein. This grain then passes through a discharge spout 15 at the lower end of the hopper and is conveyed into any suitable receptacle, the quantity of the grain thus conveyed being determined by the number of 105 rotations of the hopper. For the purpose of retarding the rotary movement of the hopper and preventing the hopper from turning backward a number of springs 16 are mounted upon the casing 9 so as to yieldingly engage the projections 12.

In the operation of the device the poises 14

are first set at the required point to determine the weight of the grain necessary to overbalance the same and depress the hopper. When thus adjusted the grain from the delivery spout 1 enters the compartment 5 of the hopper held under the same until the weight of the grain within the compartment becomes sufficient to tilt the scale beam and lower the hopper. The projection 12 which 10 was in engagement with the stop 11 is then released therefrom, whereupon the hopper rotates through a quarter revolution and discharges the grain through the spout 15. As soon as this grain has passed from the hopper 15 the poises 14 again overbalance the same and cause it to move upwardly so that the next projection 12 will engage with the stop 11 and hold the next compartment 5 in coöperative relation to the delivery spout 1. In 20 this manner the various compartments of the hopper are successively filled and discharged and the quantity of grain passing through the meter can be readily computed from the number of revolutions of the hopper.

25 Having thus described the invention, what is claimed as new is:

1. In a grain meter, the combination of a casing, a scale beam mounted upon the casing, a rotary hopper arranged within the casing and journaled upon the scale beam, poises for the scale beam, means for deliver-

ing grain to the hopper, cross bars connecting opposite sides of the hopper, a stop carried by the casing and coöperating with the cross bars to hold the compartments of the 35 hopper successively in coöperative relation with the grain delivery means, and a plurality of spring members carried by the casing and engaging the before mentioned cross bars upon the hopper to prevent accidental 40 rotation thereof.

2. In a grain meter, the combination of a casing, a U-shaped scale beam mounted upon the casing, a rotary hopper arranged within the casing and journaled between the arms 45 of the U-shaped scale beam, poises for the scale beam, means for delivering grain to the hopper, projections upon the hopper, a stop carried by the casing and coöperating with the projections to hold the compartments of 50 the hopper successively in coöperative relation with the grain delivery means, and a plurality of spring strips carried by the casing and engaging the before mentioned projections upon the hopper to prevent accidental 55 rotation thereof.

In testimony whereof I affix my signature in presence of two witnesses.

JOHN S. BLAKELY. [L. S.]
